UNITED STATES PATENT OFFICE

2,449,206

APPARATUS FOR ROLLING STEEL BARREL CHIMES

Eldon O. Dryer, Richmond, and Allen H. Meisenheimer, Jr., Berkeley, Calif.

Application January 27, 1947, Serial No. 724,574

2 Claims. (Cl. 153—32)

1

This invention relates generally to apparatus for rolling annular flanges which may be made up of a plurality of layers of material, for example steel sheets, to compress or crimp together the latter, and particularly refers to apparatus for straightening dented chimes or annular end flanges of metal or steel barrels which have become deformed by rough handling or continued use.

Heretofore such operations have been carried out by opposed rollers, generally of small diameter as compared to the diameter of the annulus to be compressed, or by rollers of small diameter which compress the annulus, or specifically a steel barrel chime, against a concentric mandrel of substantially the same outer diameter as the inner diameter of the annulus. When devices of this nature have been used, the short line contact between the roller and the chime or annular flange is generally of too small an area for effective compression or straightening, and tends rather to stretch the metal than to press or force it to the desired curvature or degree of smoothness required.

This invention comprehends broadly the provision of a rotatable member or mandrel having a rim adapted to be circumscribed or enclosed by the annulus to be operated upon, and a ring of larger diameter than the annulus surrounding said rim and said annulus, the ring being movable in the plane of the rim to contact tangentially and to compress the annulus between the ring and the circular rim of the central member. Desirably the central member is provided with means whereby it may be rotated, and such rotation, under circumstances just described, inherently causes rotation of both the annulus and the outer ring, whereby the annulus is progressively and smoothly compressed as rotation occurs. In the specific application of this invention to the straightening or removal of dents from the chimes of steel barrels, the advantages of the combination just described over the prior practices mentioned above have been very favorably demonstrated, presumably due to the similarity of the diameters of the mutually acting members.

It is an object of this invention to provide an improved means for progressively compressing an annular flange between a rigid central member and a outer ring, which may be floating, or un-driven, if desired and movable in the plane of the flange to be either substantially concentric therewith or tangential thereto.

Another object is to provide an improved apparatus for rapidly and economically straightening

2

the end flanges or chimes of cylindrical steel barrels.

Another object is to provide an improved apparatus which may conveniently be placed beneath the floor of a steel barrel handling plant, and adapted to receive and operate upon the chimes of the barrels with a minimum of handling of the latter as well as exposure of moving parts which would be a hazard to the operators.

These and other objects and advantages will be further apparent from the following specification and the attached drawing, which forms a part thereof, and which describe and illustrate a preferred embodiment of the invention as applied to barrel chime straightening.

In the drawing, Figure 1 is a plan view of a simple form of the invention, as applied to a barrel chime straightener. Figure 2 is a side elevational view of the apparatus of Figure 1, and Figure 3 is a vertical sectional view on line III—III of Figure 1, showing to an enlarged scale the relation between the annular flange, ring, and mandrel or turntable of this embodiment.

Referring to the drawing, and particularly Figures 1 and 2, reference numeral 10 designates generally a base or support member, comprising structural members 11 and 12 supporting a vertical bearing 13, and resting upon abutments or footings 14. Bearing 13 supports a heavy vertical shaft 15 on top of which is a turntable 16 having a rim 17, which could properly be designated a mandrel, and over which the annular flange or chime 18 of a steel barrel 19 is adapted to fit (Figure 3). Desirably, means for rotating shaft 15 and table 16 at a relatively low speed are provided, in this example being a motor 20 secured at one side of structural member 11 and having a speed reducing gear 21 driving a larger spur gear 22 on shaft 15 through a smaller spur gear 23 (Figure 2). Suitable means for supplying and controlling electric current to motor 20 may be provided, and need no description here.

The floating metal ring which constitutes an important part of this combination is designated 24 and has a shoulder 241 adapted to exert a downward restraining force on the upper edge of chime 18 to keep it in position during the rolling and straightening operation. In this example, ring 24 is supported rotatably in the plane of rim 17 between three circumferentially spaced flanged rollers 25, 26 and 27. These rollers are also movable selectively in the plane of rim 17, for a purpose which will be further apparent. Rollers 25 and 26 are journaled in forks 28 and 29, respectively, the latter being carried by splined or keyed

shafts 30 and 31 in supports 32 and 33 (Figures 1 and 2). Shafts 30 and 31 are slidably mounted, and are resiliently urged toward the axis of shaft 15 and turntable 16 by springs 34 and 35 and collars 36 and 37. Other types of resilient mountings mechanically equivalent to those described could equally well be used.

The third roller 27, on the opposite side of ring 24 from rollers 25 and 26, is similarly journaled in a vertical fork 38 on keyed shaft 39, the latter slidably mounted in support 40 on base member 11. On the opposite end of shaft 39 and acting selectively to urge it and roller 27 toward and from the rim 17 of turntable 16, is a power means, in this case an air-actuated cylinder and piston, generally designated 41, supplied from a suitable source of compressed air (not shown) and controlled by means such as a conventional three-way cock 42.

By the arrangement just described, when power means 41 urges shaft 39 and roller 27 toward the center of the turntable 16, ring 24 is moved against the resilient force exerted by rollers 25 and 26 to a point where its inner face will be tangential to the outer face of any annular flange or chime 48 which may be in place on mandrel 16, tending to compress the flange 48 against the rim 17. If the mandrel is rotated as by means of motor 20 and its accompanying gearing, the flange 48, together with ring 24, will be rotated thereby, progressively compressing the flange, either for the purpose of straightening dents or for any other desired operation thereon.

In order to place a barrel 19 on turntable 16 or to remove it therefrom, power means 41 is actuated to retract roller 27, whereupon rollers 25 and 26, under the influence of springs 34 and 35, will urge the relatively rigid ring 24 to a position more nearly concentric, if not actually concentric with turntable 16, leaving the chime 48 and barrel 19 free from restraint.

Desirably, the turntable 16 may be positioned as shown to rotate about a vertical axis and just below a guide opening 43 in a floor 44, to facilitate the placing, straightening, and removal of the barrels 19, although it is obvious that, for other applications, the axis could be in any plane that was convenient or desirable. Accordingly, although a single embodiment and application of

this invention has been illustrated and described, it is obvious that numerous changes and modifications could be made without departing therefrom, and all such as come within the scope of the appended claims are understood to be embraced thereby.

We claim:

1. In combination, a turntable having a rim, means for rotating said turntable, a rigid floating ring surrounding said turntable, and means for selectively positioning said ring to permit an annular flange to be received between said ring and said turntable and for urging said ring toward said rim progressively to compress said flange radially therebetween when said turntable is rotated, said means comprising a plurality of circumferentially spaced rollers and means for resiliently urging some of said rollers toward and from said rim, at least one of said rollers being positively movable toward said rim.
2. In combination, a turntable having a rim, means for rotating said turntable, a rigid floating ring surrounding said turntable, and means for selectively positioning said ring to permit an annular flange to be received between said ring and said turntable and for urging said ring toward said rim progressively to compress said flange radially therebetween when said turntable is rotated, said means comprising three circumferentially spaced flanged rollers, two of said rollers being resiliently mounted to move in the plane of said rim, the third roller being provided with means for positively urging it toward said rim.

ELDON O. DRYER.
